CLAIM

The ornamental design for a reclosable seamless box, as shown and described.

DESCRIPTION

FIG. 1 is a top perspective view of a reclosable seamless box showing our new design, in an open condition;

FIG. 2 is a perspective view of the reclosable seamless box in partly folded, frustum shaped, open-ended condition;

FIG. 3 is a perspective view of the reclosable seamless box with a bottom end in partially folded condition;

FIG. 4 is a perspective view of the reclosable seamless box with a bottom end in completely folded and closed condition;

FIG. 5 is a perspective view of the reclosable seamless box with a bottom end completely folded and closed, and a top end in open condition;

FIG. 6 is a perspective view of the reclosable seamless box with a bottom end completely folded and closed, and a top end in partially folded condition; and,

FIG. 7 is a perspective view of the reclosable seamless box with the bottom end and the top end in completely folded and closed condition.
